CLAIM

The ornamental design for the tool for body tempering and trigger points having interchangeable parts as shown and described.

DESCRIPTION

FIG. 1 is a top, front perspective view of a tool for body tempering and trigger points having interchangeable parts, of which comprises a double body connected by a connector, four interchangeable heads and an interchangeable handle; FIG. 2 is a top, rear perspective view thereof, an exemplary interchangeable head (pointed) and the interchangeable handle in place;

FIG. 3 is a left side view thereof, of which the right-side view is the same;

FIG. 4 is a top view thereof, the bottom view being a mirror image thereof;

FIG. 5 is a front view thereof; and,

FIG. 6 is a rear view thereof.

The broken lines in the figures illustrate the portions of the design that form no part of the claimed design.

1 Claim, 3 Drawing Sheets
